UNITED STATES PATENT OFFICE.

CHARLES T. MASON, OF SUMTER, SOUTH CAROLINA.

IGNITION DEVICE FOR EXPLOSIVE-ENGINES.

1,030,243.

Specification of Letters Patent. Patented June 18, 1912.

Application filed November 23, 1910. Serial No. 593,810.

To all whom it may concern:

Be it known that I, CHARLES THOMAS MASON, a citizen of the United States, residing at Sumter, in the county of Sumter 5 and State of South Carolina, have invented certain new and useful Improvements in Ignition Devices for Explosive-Engines; and I do hereby declare the following to be a full, clear, and exact description of the 10 invention, such as will enable others skilled in the art to which it appertains to make and use the same, reference being had to the accompanying drawings, and to the figures of reference marked thereon, which form a 15 part of this specification.

My invention relates to means whereby an electric generator may be associated with an explosive engine for ignition purposes, and consists of means whereby the generator is 20 operated by the engine, or by hand at will, the latter arrangement admitting of the production of a spark while the piston or pistons of the engine are in any desired position, either in motion or at rest.

25 My invention also consists in so arranging the generator that the armature may be moved by the engine into the firing position ready to produce a spark, and held in this position until released by hand, thereby enabling the ignition to be effected at the will 30 of the operator.

Figure 1 is a front elevation of my invention. Fig. 2 shows the trip lever and the trigger catch mechanism associated therewith. Fig. 3 shows the trip lever mechanism being actuated by hand.

The same figures of reference designate the same parts wherever they are shown.

The preferred form of generator used 40 with my invention is of the so-called magneto type, and consists of permanent magnets 11 between the ends of which exist a magnetic field. In this is placed an armature, the shaft of which is indicated at 15, this 45 shaft being supported at each end of the machine by suitable end plates. It will be understood that the rear end plate not shown in the drawing, forms a support for the armature shaft and the insulated terminal 50 connected to one end of the armature winding, the other end of the winding being connected to the frame of the machine. This construction is already well known in the art. To the front end plate 16 is attached the 55 bolts 17 and 18 for holding one end of the

closed springs 6 and 7, the other end of these springs being attached to the pins 19 and 20 on the trip lever 1. This plate also carries a support 23 for the trigger catch 13 and handle 2. A weight 12 is attached to the 60 trigger mechanism so it will remain placed in either a vertical or horizontal position.

Attached to the trip lever 1 in any suitable manner at 24 is the igniter rod 4, the end of which engages the movable member 10 of 65 the igniter, this movable member normally contacting on a fixed member 25 within the cylinder of the engine. Between these members the spark for ignition is produced, as they are connected in circuit with the 70 armature winding of the magneto.

The magneto is mounted on the engine in such a position that the cam pin 8 attached to the cam disk 9 mounted on the cam shaft 21, or some other part of the engine, will—as 75 it moves in the direction of the arrow—engage the end 22 of the trip lever 1 and move same to one side. This movement is against the tension of the springs 6 and 7, and as soon as pin 8 passes beyond 22 the springs 80 exert their force on the trip lever 1, and cause the armature connected thereto to violently oscillate in the magnetic field, producing an electrical current. It will also be noted that at the same time, the rod 4 is pushed out- 85 wardly, by reason of the trip lever oscillating beyond its normal position to the right, and the contact points of the igniter are separated, a spark being produced at the same time that the electrical current is at its 90 maximum, thereby igniting the charge. Normally, the igniter points are closed producing a closed circuit through the armature winding.

It is evident that the magneto and the 95 igniter will be timed and operated in proper relation to each other as long as the cam shaft or other portion of the engine is in motion, but it is often desirable to produce a spark when the engine is not moving, as 100 when starting the engine—particularly in large engines which are difficult to move so as to actuate the magneto as just described—therefore, I provide the following means for operating the magneto independently of 105 movement from the engine.

In the cam lever 1, I provide a socket 3 in which may be placed a lever 5. The trip lever may then be drawn to the right as shown in Fig. 3 until the end 14 of same is 110

hooked under the trigger catch 13 as shown in Fig. 2, the weight 12 being omitted for the sake of clearness. It will now be noted that the springs are under tension. When it is desired to produce a spark, the trigger 2 is drawn to the right, thereby releasing the end of trip lever 1 from under the trigger catch 13, and the armature is oscillated by the springs as previously described, 10 and the spark produced in the usual manner, this being accomplished without any movement on the part of the cam shaft or other part of the engine ordinarily used for operating the magneto. As soon as the engine 15 has been started, the lever 2 is placed in a horizontal position thereby raising the trigger catch 13 so that the end 14 of the trip lever will not catch under same as it is regularly moved back and forth by the engine.

If it is desired to stop the engine it is only necessary to place trigger 2 in a vertical position whereupon the end 14 of the trip lever will hook under the trigger catch 13, 25 and the magneto will be locked, thereby stopping the engine. It will be observed that if the engine stops under compression, the simple release of the trigger mechanism will cause the magneto to generate and start 30 the engine.

I am aware that it is not new to operate a generator for ignition purposes by some moving part of the engine it is used with, but with devices of this character heretofore used, especially with large engines which cannot be moved by hand, it is necessary to have battery ignition for starting, as no provision is made for operating the magneto independently of the engine, and 40 it cannot generate until the engine is in motion. After the engine is started, it is customary to disconnect the battery and substitute therefor the magneto. This requires switches and considerable wiring. With my 45 invention, it is obvious that the spark can be generated at will by the operation of the magneto by hand, thereby eliminating the use of the battery and the switch, wiring, etc., incident thereto. This also enables the 50 engine to be stopped by locking the magneto, and started by releasing the magneto as previously described, and it is not detrimental to the magneto to remain on short circuit while the engine is not running, 55 whereas, if batteries are used, they would be exhausted unless the switch was opened, which is often forgotten.

While I have shown but one type of generator, same being actuated from the cam 60 shaft of the engine, and one means of operating the spark gap or igniter, it will be understood that my invention is not limited to the precise form herein described, as other forms of magneto and means of operating 65 same in connection with the spark gap are

obvious to those skilled in the art, and may be used without departing essentially from the features herein claimed by me.

Having thus described my invention, I claim and desire to secure by Letters Patent, 70 the following:

1. An ignition device for explosive engines comprising an oscillating dynamo, a trip lever on the armature of said dynamo, a make and break spark gap actuated by said trip lever, springs for restraining the trip lever, means for holding the trip lever against the tension of said springs, and means for releasing the trip lever manually.

2. In an ignition device for explosive engines, the combination of an oscillating dynamo, a trip lever carried thereby, springs for restraining said trip lever, a make and break spark gap actuated by said springs, means operated by the engine for moving 35 the trip lever to the firing position, means for holding the trip lever at the firing position, and means for releasing the trip lever to cause an oscillation of the armature and the operation of said make and break igniter 90 in unison, independently of movement of the engine.

3. An ignition device for explosive engines comprising an electric generator having an oscillating armature, a trip lever for said generator, springs restraining said trip lever, a firing rod oscillated by said trip lever, sparking mechanism actuated by said rod, means for holding the trip lever against the tension of said springs, and means for 100 releasing the trip lever to produce a spark substantially as described.

4. In an ignition device for explosive engines, the combination of a suitable dynamo, an oscillating armature in said dynamo, 105 plates for supporting the armature, a trip lever carried by the armature shaft, springs connected to the trip lever, means for moving said trip lever against the tension of said springs, a trigger positioned near the 110 trip lever so as to engage and hold same under tension, and means for releasing the trigger.

5. In an ignition device for explosive engines, the combination of a suitable 115 dynamo, an oscillating armature in said dynamo, end plates supporting the armature, a trip lever carried by the armature shaft, springs between the trip lever and one end plate, means for moving said trip lever 120 against the tension of said springs, and trigger mechanism for holding the armature under tension and releasing it at will.

6. In an ignition device for explosive engines, a definitely timed oscillating generator of electricity in combination with a make and break igniter, operating means for said generator, means for manually stopping the oscillation of said armature and to hold same locked ready to generate, and 130

means for releasing said armature and operating the igniter to produce a spark, substantially as described.

7. In an ignition device, a dynamo having
5 an armature adapted to be oscillated, an end plate for said armature, a trip lever on said armature, springs between said trip lever and the end plates, a make and break igniter mechanically connected to said trip lever and working in unison therewith, trigger mechanism positioned near said trip lever to hold same in a given position, means for operating the trip lever, and manual means whereby said trigger mechanism may
10 be thrown in action to hold the trip lever without stopping said operating means.
- 15 8. A dynamo having an armature adapted

to be oscillated, spring mechanism connected to said armature whereby it is maintained in a predetermined normal position, manual 20 means for moving said armature against the tension of said spring mechanism and out of the normal position, locking means for holding said armature out of the normal position, and means for releasing said locking means 25 whereby the armature is permitted to oscillate and produce a current, substantially as described.

In testimony whereof I hereunto affix my signature in the presence of two witnesses. 30

CHARLES T. MASON.
